UNITED STATES PATENT OFFICE.

HARRY S. GORE, OF MIDWEST, WYOMING; CATHERINE GORE ADMINISTRATRIX OF
SAID HARRY S. GORE, DECEASED.

FISHING TOOL.

Application filed July 11, 1927. Serial No. 204,906.

The present invention pertains to fishing tools and it is primarily sought to provide a simple rugged tool of this character which may be used for removing broken sucker rods from well casings.

Although primarily intended for the use mentioned, it is contemplated that the invention may be embodied in numerous forms to adapt it to other analogous uses. Among 10 these may be mentioned the recovery of drill bits, wire line, rope sockets and other accessories used in well drilling.

The invention is in the form of a fishing tool of the ball or ball bearing type in which 15 an annular series of metal balls located within the body of the tool is adapted to cooperate with the surrounding parts so as to readily and firmly grip the sucker rod or other object being recovered when the object once enters the tool and the latter is raised in the well.

Heretofore in this type of tool considerable difficulty has been encountered because the heavy paraffin and mud which is present 25 in the well gets between the balls and into their runways thereby clogging these spaces and preventing the balls from functioning properly to grip the object. It is an important object of this invention to reduce 30 to a minimum the likelihood of the balls failing to function properly due to the causes just mentioned.

A further object is the provision of means for positively urging the balls into firm engagement with the object at all times, these means being of such character that there is practically no chance of mud or paraffin interfering with their proper operation.

Further objects are the furnishing of a 40 grapping or fishing tool which operates much more effectively than other types and which, due to the nature of its construction, has a much longer life and is considerably less expensive to manufacture; also a tool in which replacements are quite inexpensive.

With these and such other objects in view as will appear from the following detailed description, reference is had to the accompanying drawings in which there is shown 50 a practical embodiment of the invention.

Figure 1 represents a vertical longitudinal section of the tool taken centrally thereof, the parts of the tool being shown in the positions which they assume as a section of a

sucker rod or the like is about to enter the 55 tool;

Fig. 2, a front elevational view, the parts being broken away to show the interior construction and arrangement after the sucker rod section has entered the tool and the latter is being raised to remove the sucker rod 60 section from the well;

Fig. 3, a fragmentary vertical sectional view, similar to Fig. 1, showing the details of the lower end of the body of the tool including the ledge on which the balls are supported; and

Fig. 4, a front elevational view, partly in section, showing the details of the combined spring shoe and ball retainer ring.

In the drawings, there is shown at 1 a tubular metal member which comprises the body of the tool. The wall of the body portion 1 is thickened near its lower end so as to form a restricted opening 2 therethrough. 70 This opening 2 is adapted to receive the upper end of the sucker rod section 3 and is made sufficiently large so as to readily permit entrance of sucker rod 3 or any other object which it is sought to recover. In order to guide the body portion 1 of the tool over the sucker rod 3 and cause the latter to enter the opening 2, the body portion 1 is provided on its lower end with the usual tapered surface 4. The wall of the upper portion of the body 1 is of uniform thickness, but near its lower end, above opening 2, it is thickened so as to provide a downwardly and inwardly tapered surface or contracted portion 5 which merges into an annular ledge 6 on which rests an annular series of balls 7. It is to be noted that ledge 6 is somewhat concave in cross section so as to hold the balls 7 thereon and prevent them from falling through the opening 2. 80

Ledge 6 and opening 2 are so arranged and proportioned, and balls 7 are of such size, that, as shown in Fig. 1, the balls project slightly beyond the inner periphery of the ledge. This places the balls 7 in such position that when sucker rod section 3 enters the tool through opening 2 the balls are engaged by the sucker rod, or other object which is of a diameter greater than the distance between 90 diametrically opposite balls 7 of the series, and caused to move off of ledge 6 and roll up the inclined surface 5. Since surface 5 tapers upwardly and outwardly, as balls 7

roll up this surface the distance between diametrically opposite balls will gradually increase, thereby permitting passage of sucker rod section 3 through the annular series of 5 balls to the position shown in Fig. 2.

With the parts in this position it will be impossible to withdraw the tool from the sucker rod 3 by pulling it upward, since any upward movement of the tool will only 10 cause the balls 7 to tend to roll down the inclined surface 5 and bind more tightly on the periphery of the sucker rod.

The upper end of body portion 1 is threaded interiorly to receive an exteriorly 15 threaded connector 8, the latter being provided with a flange 9 adapted to abut against the upper end of body portion 1. Connector 8 is provided with a central depending tubular portion 10, of smaller di- 20 ameter than the body portion of the connector and of a length so that it extends almost down to the annular series of balls 7. Tubular portion 10 is open at its lower end and at its upper end connects with a T- 25 shaped fluid passage 11 provided in the body portion of the connector. Passage 11 connects the interior of the tool with the interior of the well above the body of the tool so as to provide for the free passage of oil, 30 water, etc.

Connector 8 at its upper end is provided with a reduced threaded portion 12 which engages in a threaded socket in the lower end of a suitable handling means 13, where- 35 by the tool may be raised and lowered in the well.

The lower extremity of the tubular portion 10 of connector 8 is chamfered or beveled slightly downwardly and outwardly at 40 its inner periphery 14 so as to facilitate the entrance of sucker rod 3 into the tubular portion 10. On the exterior thereof, at its lower end, depending portion 10 of connector 8 is chamfered or beveled so as to pro- 45 vide a downwardly and inwardly inclined portion 15, which, when the parts are as- sembled, has its surface in substantial parallelism with the surface of the inclined portion 5 or the body 1 of the tool. In addition, the parts are so arranged and proportioned that the space between inclined portions 5 and 15 is sufficient to just permit the free passage or movement of the annular series of balls 7 as they roll up and down 50 the inclined surface in the operation of the device. With this arrangement of parts it will be seen that maximum provision is made to prevent access of heavy paraffin and mud into the series of balls 7 and the run- 55 ways or spaces in which they operate.

In order to prevent the accidental dis- placement of balls 7 from their ledge 6 and to assure their firm engagement with the sucker rod 3, at all times, there is provided 60 a ball retainer ring or spring shoe 16 which

fits in the annular space or chamber 17 be- 70 tween the body portion 1 of the tool and the tubular extension 10 of connector 8, so that it may freely slide therein on the lower end of extension 10. The details of member 16 are clearly shown in Fig. 4. The diameter of the opening 18 through this member 16 is uniform throughout its length. The outside diameter of the member, however, is uniform at the upper portion of the mem- 75 ber, but the member at its lower end is tapered downwardly and inwardly so as to provide an inclined surface adapted to en- gage and coact with the correspondingly in- clined surface 5 of the body portion 1 of 80 the tool.

Disposed in annular chamber 17, between member 16 and a shoulder 20 formed near the upper end of extension 10 of connector 8, 85 is a coil spring 21. Spring 21, being under tension, serves at all times to force ring member 16 downwardly into engagement with the annular series of balls 7. This not only serves to maintain the balls on their ledge 6 when the device is not in use, but 90 as shown in Fig. 2, when an object is being retrieved, spring 21, through member 16, tends to force balls 7 down inclined surface 5 and cause them to contract about and firmly grip the object. Thus when the tool 95 is raised by means of member 13, after the object has once passed into the tool, it is impossible for the tool to be pulled off of the upper end of the object and thus it may be raised out of the well.

The object having been recovered from the well the tool may be removed therefrom by unscrewing handling means 13 and connector 8 and removing spring 21, ring 16 and balls 7 from the tool.

What I claim is:—

1. The combination in a fishing tool of a tubular body portion having an opening at its lower end, said body portion being pro- 110 vided internally with a ledge surrounding said opening; an annular series of balls dis- posed on the ledge and projecting in line with said opening, said ledge being shaped to normally retain the balls thereon; and yieldable means tending to maintain said balls on the ledge, the body portion of the tool being provided internally with an up- 115 wardly and outwardly inclined surface merging into said ledge.

2. The combination in a fishing tool of 120 a tubular body portion having a central opening at its lower end and open at its upper end; a connector mounted removably in the upper open end of said body portion and having a central tubular depending por- 125 tion extending into the body portion so as to form an annular chamber therebetween, the body portion being formed internally with an annular ledge surrounding said opening in its lower end; an annular series 130

of balls disposed on said ledge, the body portion being tapered upwardly and outwardly adjacent said ledge to permit expansion and contraction of the annular series of balls in their movements; a ring slidably mounted in said annular chamber and having its lower end bearing on said series of balls; and spring means located in said annular chamber above the ring member and urging the ring member downwardly against said balls.

3. In a fishing tool, the combination of a tubular body portion having an opening in the lower end thereof adapted to receive an object to be retrieved, said body portion also being open at its upper end; a removable connector mounted in the upper end of the body portion and having a tubular extension extending downwardly into the body portion, the lower extremity of said extension being chamfered on its inner periphery to facilitate the entrance of an object; an annular series of balls disposed on an annular ledge formed interiorly of the body portion of the tool about the opening in the lower end thereof; and yieldable means tending to maintain the series of balls on said ledge, the body portion being inclined upwardly and outwardly on its interior immediately adjoining said ledge.

4. A fishing tool comprising a tubular body portion, the upper end of which is open and the lower end of which is provided with a central contracted opening to receive an object to be retrieved; a connector removably mounted in the upper end of the body portion, the body portion being provided interiorly with an annular ledge surrounding said opening in its lower end and an upwardly and outwardly inclined portion adjoining said ledge; an annular series of balls disposed on said ledge and projecting in line with said opening; and yieldable

means tending to maintain the balls on their ledge, said connector being provided with a central depending portion, the lower end of which is tapered upwardly and outwardly and extends into close proximity to the annular series of balls, there being only sufficient space between said inclined surfaces on the body portion and said extension to permit free movement of the series of balls.

5. A fishing tool, comprising in combination, a tubular body portion having a central opening in its lower end and said end provided exteriorly with an inclined surface adapted to guide an object to be retrieved into said opening, the body portion also being open at its upper end; a connector removably mounted in the upper end of the body portion and having a central depending extension projecting downwardly into said body portion, there being fluid passages connecting the interior of the body portion with the outside of the tool above the body portion through said extension; a ring slidably mounted between the body portion and said connector extension, the body portion being provided interiorly with an annular ledge and an adjoining upwardly and outwardly inclined portion surrounding the opening in the lower end thereof; an annular series of balls disposed on said ledge and projecting in line with said opening; and a coil spring disposed in said body portion between the connector and the ring to urge the ring downwardly against the series of balls, said connector extension being externally beveled downwardly and inwardly on its lower end so as to coact with said inclined surface on the body portion to provide a runway for the annular series of balls.

In testimony whereof I have signed my name to this specification.

HARRY S. GORE.
